(No Model.)

F. J. RENCHARD.

LUBRICATOR.

No. 278,741.

Patented June 5, 1883.

UNITED STATES PATENT OFFICE.

FRANCIS J. RENCHARD, OF DETROIT, MICHIGAN.

LUBRICATOR.

SPECIFICATION forming part of Letters Patent No. 278,741, dated June 5, 1883.

Application filed December 30, 1882. (No model.)

To all whom it may concern:

Be it known that I, FRANCIS J. RENCHARD, a citizen of the United States, residing at Detroit, in the county of Wayne and State of Michigan, have invented certain new and useful Improvements in Lubricators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in lubricators; and it pertains to that class in which the feed of oil is ascertained as it passes upward through water in a glass indicator-tube.

The object of my invention is to simplify the 20 construction and diminish the number of parts of the lubricator, whereby the expense of construction is reduced.

25 My invention is further explained by reference to the accompanying drawings, in which Figure 1 represents a vertical section. Fig. 2 is a side view. Figs. 3 and 4 are detail views.

Like parts are represented by the same reference-letters throughout the several views.

The condensing-chamber A, neck B, connecting-trunk C, steam-tube D, and glass cage E are cast in a single piece, and the oil-receptacle F and glass cage G are also cast in a single piece. These two pieces are connected together by the screw-joint H upon neck B. Communication between the oil and water chambers is closed by the plug I, which plug is located at the lower end of said neck B, while the connecting-trunk C and the upper glass cage are formed at the upper end of said neck. To the 40 lower side of said plug I is a curved U-shaped tube, J, through which water is conducted from the condensing-chamber into the oil-receptacle.

U is a valve for regulating the flow of water 45 from the condenser to the oil-receptacle.

The trunk C is provided with two passages, a and b, one connecting directly with the condensing-chamber A, and the other with the upper glass cage, E.

50 L is the oil-filling hole.

M is a glass indicator-tube, which is supported by the cages N and O. (Shown in Fig. 3.) The object of the glass tube M is to show the quantity of oil in the receptacle F. The glass tube M and the supporting-cages may, however, be dispensed with, if desired, and the oil-filling hole formed in the side or top of the oil-receptacle, as shown in Fig. 2.

The passages to and from the glass tube K are respectively governed by the screw-valves 60 P P. The knobs of the valves P P are made of wood or other poor conductors of heat, to prevent contact of the hand with the metal. The knobs are formed of two disks, R and S, upon one of which is a stud, T, which is inserted through an opening in the end of the valve-shank, when the disk, which is provided with a central opening, is then pressed upon said stud, and thus retained upon the opposite side of said valve, as shown in Fig. 4.

70 My lubricator operates as follows: When the boiler is made steam-pressure, the valves U and P are closed to exclude steam while filling the oil-receptacle F. The oil-receptacle being filled, said valves U and P are opened, 75 when steam enters the condensing-chambers through passage a and steam-tube D, when it condenses and the water passes into the oil-receptacle F through tube J. The water thus entering floats the oil, causing it to escape, 80 drop by drop, up through glass tube K, from whence it passes through passage b into the steam-pipe.

Having thus described my invention, what I claim as new, and desire to secure by Letters 85 Patent, is—

1. The chamber A, neck B, trunk C, and glass cage E, cast in a single piece, said trunk being provided with separate steam and oil ducts and formed in line with the said glass 90 cage E, at the upper end of the glass tube K, in combination with the oil-receptacle F and glass cage G, said cage G being formed at the upper end of said oil-receptacle, substantially as set forth.

2. The combination of reservoir A, neck B, trunk C, stopper I, curved tube J, and valve U, said stopper I being formed at the lower end of said neck, below said trunk, the length of said neck being such as to permit said side 100

glass to be interposed in the space between said trunk and the top of said oil-receptacle, substantially as set forth.

3. The combination, with the oil-reservoir 5 F, stopper I, and curved tube J, of the glass indicator-tube M, provided with cages N and O, and oil-filling hole L, as set forth.

In testimony whereof I affix my signature in presence of two witnesses.

FRANCIS J. RENCHARD.

Witnesses:

JOHN SEBERT,
GEORGE GATES.
